UNITED STATES PATENT OFFICE.

CLARENCE P. COOK, OF WATERBURY, CONNECTICUT, ASSIGNOR TO SCOVILL MANUFACTURING COMPANY, OF WATERBURY, CONNECTICUT, A CORPORATION OF CONNECTICUT.

VANITY BOX.

Application filed December 28, 1922. Serial No. 608,878.

This invention relates to certain improvements in small boxes for holding toilet accessories of that class commonly or popularly known as vanity boxes.

5 These vanity boxes are largely used for carrying rouge and powder, either in compact or loose form with the accompanying puffs, and must be, to be commercially practicable, of a size small enough to readily slip 10 into a handbag, pocketbook or the like. In using these boxes it is very desirable that provision be made for a larger amount of powder to be contained therein than rouge, as the powder is used in greater quantities 15 than the rouge. It is, also, desirable in this class of boxes that the rouge and powder in either compact or loose form be arranged in the box so that they may be readily exposed for use; that the box may be readily 20 refilled with rouge and powder either with what is known as a refill, that is, a powder carrier which may be purchased and inserted in the box, or with new powder or rouge compacts, or with loose powder.

25 It is the especial object of the present invention to provide one of these combination powder and rouge boxes or vanity cases, in which the box is so shaped as to permit the use of a greater quantity of powder than of 30 rouge, the powder and rouge being held in the box side by side in the same plane so that both may be exposed for use on lifting the cover of the box, suitable means being provided for separating the powder and 35 rouge compartments.

It is a further object of the invention to provide a refill holder for holding the powder and rouge, this holder having compartments of unequal size so as to provide for 40 a greater amount of powder than rouge, this holder being preferably removable from the container so that it may be removed when its contents have been depleted or if desired for other purposes, and replaced by another 45 filled holder, so that the box itself is not discarded but may be used repeatedly.

A further object of the invention is to provide a box or vanity case of this character, which shall be attractive in appearance, simple and easy to use, and of cheap but durable construction.

With these and other objects, not specifically referred to, the invention consists in certain novel parts, arrangements and com-

bination, which will be described in connection with the accompanying drawings, and the novel features thereof pointed out in the claims hereunto annexed. 55

Referring now to these drawings which illustrate a preferred embodiment of the invention— 60

Figure 1 is a top view of the box with the cover open.

Figure 2 is a sectional view, the section being taken on line 2—2 of Fig. 1. 65

Figure 3 is a sectional view, the section being taken on line 3—3 of Fig. 2.

Figure 4 is a perspective view of the improved refill holder removed from the box.

Referring now to these drawings, the box 70 or case comprises a bottom member 1, having a flange 2 rising therefrom, this flange being slightly inset as shown at 3 to form a stop. This box is closed by a cover 5 having a flanged edge 4 which telescopically 75 engages the inset flange 3 of the bottom and seats against the shoulder formed by the insetting of the flange when the box is closed. If desired, a knob catch 6 may be provided for holding the parts in closed 80 relation. In the best constructions a mirror is provided for the user when applying the cosmetics, and as shown this mirror, marked 7, is carried in the cover of the box, being held in position by a rim 8, best shown in 85 Fig. 1.

In accordance with the invention this box is formed so as to provide a powder compartment and a rouge compartment of 90 smaller dimensions than the powder compartment, so that more powder than rouge can be carried in the box, and these compartments are arranged so as to lie in the same plane, so that both the compartments are exposed by the single movement of opening the cover of the box. 95

While various configurations of the box may be adapted for effecting this result, in the best constructions as illustrated, the box will be generally triangular in shape, the 100 rouge compartment being formed in one of the apices of the triangle, and the powder compartment being formed adjacent thereto and taking up substantially the remainder of the box, this construction providing a 105 powder compartment of the required dimensions to provide powder and rouge in such quantities that both will be exhausted

at about the same time, and forming a box of the desired small size suitable for carrying in a handbag, pocketbook, or the like.

While the powder and rouge compartments which are indicated by the numerals 9 and 10, may be formed in various ways, in constructions embodying the invention in its best form, these compartments will be formed in a holder designated generally by the numeral 12, this holder being removably held in the box. As illustrated, this holder is in the form of a plate of light metal stamped to form the powder compartment 9, and having curved end walls 13 and side walls 14 rising from a bottom 15. Located closely adjacent the powder compartment is the rouge compartment 10, having a bottom 11, this compartment being formed by depressing the plate at this point, flats 16 being preferably left at each side and to the rear of the rouge compartment from which projects upwardly a partition member 17 extending across the holder which acts to separate the powder and the rouge, and tends to prevent the respective rouge and powder puffs from being accidentally moved one upon the other. This holder is held in the box so as to prevent its being accidentally displaced, but so that it may be readily removed therefrom when desired.

In the particular construction illustrated, the bottom 1 and the cover 5 are secured together in pivotal relation on a hinge 18 located about centrally to one side of the box, being as shown at the back of the powder compartment, and about centrally thereof. The back wall of the holder is formed with a spring member, which in the construction shown is arranged to engage under the hinge and retain the holder in the box under light spring tension. To effect this the back wall of the holder is slit as at 20 to form a spring tongue 21, this tongue being turned outwardly slightly as shown at 22 away from the walls. The back wall of the box is cut down slightly at each side of the tongue so as to clear the hinge 18, as indicated at 23 in Fig. 4. With this construction the holder is easily snapped into position in the box, and the tongue is readily engaged from beneath the hinge to free the holder when it is desired to remove it.

The powder and rouge used in this box are preferably in the form of the well known compacts (not illustrated), and may be secured in the holder by gluing them to the bottom of the compartments.

While the invention has been shown and described in what is believed to be its best form, it will be understood that variations in the shape of the box, and in the form and construction of the holder may be made without departing from the invention, as defined in the claims appended hereto.

What I claim is:

1. A box for holding toilet accessories comprising a bottom and a cover pivotally associated therewith, one of these members being provided with separated compartments lying side by side in substantially the same horizontal plane, the powder compartment being of greater dimensions than the compartment for holding the rouge, the area of the two compartments being substantially that of the member in which they are provided.

2. A box for holding toilet accessories comprising a bottom and a cover pivotally associated therewith, one of these members being provided with separated compartments lying side by side in substantially the same horizontal plane, the powder compartment being of greater dimensions than the compartment for holding the rouge, the area of the two compartments being substantially that of the member in which they are provided, and a reflecting means carried by the other member.

3. A box for holding toilet accessories comprising bottom and cover members wider at the back than at the front, a partition member dividing the bottom member into compartments of different sizes for holding powder and rouge, the powder compartment being larger than the rouge compartment, the two compartments having an area substantially that of the bottom member, and means for removably securing the partition in the bottom of the box.

4. A box for holding toilet accessories, comprising bottom and cover members, and a refill holder removably secured in the bottom member, and having spaced compartments for powder and rouge lying side by side in the same horizontal plane, the powder compartment being of greater size than the rouge compartment, the area of the two compartments being substantially that of the holder.

5. A box for holding toilet accessories comprising bottom and cover members wider at the back than at the front, and a refill holder wider at the back than at the front removably secured in the bottom member and having separated powder and rouge compartments, one of these compartments being of greater size than the other.

6. A box for holding toilet accessories comprising bottom and cover members pivotally united by a hinge, a refill holder having separated powder and rouge compartments of different sizes in the bottom of the box, and a spring tongue integral with the holder for holding the refill removably in position.

7. A box for holding toilet accessories having a bottom and a cover pivotally united by a hinge, a refill holder having separated powder and rouge compartments of different

sizes in the bottom of the box, and a spring tongue struck out from a wall of the refill and adapted to take under the hinge to removably hold the refill in the box.

8. A box for holding toilet accessories, comprising bottom and cover members substantially triangular in shape, a triangular refill holder in the bottom of the box and having separated powder and rouge compartments, and spring means for holding the refill in the box.

9. A box for toilet accessories having a bottom member and a cover, a refill holder comprising a plate formed with depressions to provide a powder compartment and a smaller rouge compartment in the same horizontal plane, the area of the compartments being substantially that of the holder, a partition above the top surface of

the plate between the compartments, and means for removably holding the refill in the box.

10. A refill holder for boxes of the class described, comprising a plate having portions of different sizes depressed to form walled powder and rouge compartments and bottoms therefor, and a spring tongue carried by the holder for securing it in a box.

11. A refill holder for boxes of the class described, comprising a plate having portions of different sizes depressed to form walled powder and rouge compartments and bottoms therefor, and a spring tongue cut out from one of the compartment walls for securing the refill in a box.

In testimony whereof, I have hereunto set my hand.

CLARENCE P. COOK.
